Primary Examiner—B. J. Bullock**Attorney, Agent, or Firm—Mason, Fenwick & Lawrence****[57] CLAIM**

The ornamental design for a garment hanger bar for air travel garment boxes, as shown and described.

DESCRIPTION

FIG. 1 is a perspective view of a movement restraining garment hanger bar for air travel garment boxes, showing my new design;

FIG. 2 is a front elevational view thereof, the opposite or rear elevation being the mirror image thereof;

FIG. 3 is an end elevational view thereof, the opposite end elevation being the mirror image thereof;

FIG. 4 is a top plan view thereof; and,

FIG. 5 is a bottom plan view thereof.

FIG. 1

FIG. 2

FIG. 3

FIG. 4

FIG. 5
